Application November 1, 1938, Serial No. 238,182

3 Claims. (Cl. 30—162)

This invention relates to knives and particularly knives such as are used in the furriers' art in the cutting and trimming of pelts.

It is an object of this invention to provide a furriers' knife which will facilitate the cutting and preparation of furs; to provide a knife which is extremely compact and relatively inexpensive to manufacture; to provide a furriers' knife which has, in combination, facilities for preliminary marking of the pelts in preparation for cutting of the same, and which includes the desirable factors of safety.

These and other objects will become more apparent as this specification proceeds and the novelty thereof will be particularly pointed out in the appended claims.

The objects hereinbefore referred to are achieved through the provision of a knife having a thin handle portion, shaped to fit the hand, and into which the blade is retractable when not in use as a safety precaution. Additionally, provision is made for the marking of the pelts by providing an extremely thin edge at one portion of the handle member to be used in marking by impression and by the provision of a pivotal retainer means in one end of the knife for a marking medium such as, for example, chalk.

In the drawing forming a part hereof:

Figure 1 is a perspective view of the furriers' knife forming the subject matter hereof, with the blade thereof in projected position.

Figure 2 is a longitudinal section of the knife shown in Figure 1.

Figure 3 is a cross-section taken along the line 3—3 of Figure 2.

Figure 4 is a cross-section taken along the line 4—4 of Figure 2.

Figure 5 is a longitudinal section of the knife, similar to Figure 2, but showing the blade in its retracted position and the pivotal chalk retainer member swung outwardly.

Figure 6 is a sectional plan view taken along the line 6—6 of Figure 2.

Figure 7 is a perspective view of the blade carrier, and

Figure 8 is a perspective view of the preferred form of blade.

The numeral 10 designates a relatively thin knife handle having a relatively deep end portion 11 which tapers away to a narrower end portion 12, the purpose of this being to provide a handle which is readily adaptable to the grip. The handle member 10 has a longitudinally extending recess 13 therein in which a blade carrier 14 is slidably received. The recess 13, it will be noted,

is open at one end of the handle member 10 and is reduced to form a bore at its opposite end, as at 15, to receive pin 16 on blade carrier 14. The depth of the recess 13 is such that it will conceal a blade 18 when the carrier member 14 is drawn rearwardly to substantially the end of the enlarged portion of the recess 13.

It will be noted from Figures 2, 5 and 6 that a helical spring member 20 is disposed in the reduced portion of recess 13 and surrounds the pin 16 of blade carrier 14, and normally urges blade carrier 14 into its outermost position (see Fig. 2) projecting the blade 18.

The blade carrier is notched as at 22 at its outer end (see Figure 7) and is adapted to be engaged by the toe 27 of the latch 23 and thereby locked in its innermost position (see Figure 5). Latch 23 is disposed in an aperture 24 in top of handle member 10, being attached for pivotal movement therein, and has a thumb piece 25 projecting out of the handle and a toe 27 engaging the notch 22 in blade carrier 14. A flat spring 26 disposed in the handle member above the recess 13 bears against and normally urges the toe 27 of latch 23 downwardly for engagement with the notch 22 of the blade carrier 14 when the latter is in its innermost position (see Figure 5).

To limit the outward movement of carrier 14 and facilitate the retraction of the blade 18 and its carrier 14 into the handle 10, we provide a longitudinally extending slot 30 in the side of the handle member 10 through which projects the shank of the thumb screw 31 for engagement with carrier 14. It will be understood that while spring 20 causes blade 18 to be projected upon release of latch 25, the blade and its carrier must be manually retracted into the recess 13 by thumb screw 31.

The particular construction of the blade carrier 14 is illustrated to best advantage in Figure 7 of the drawing. A plate 32 of rigid material such as metal or the like, has a relatively thicker butt end 33 to which pin 16 is attached. The butt end 33 of carrier 14 has two shoulder portions cut therein in the reduction of its size to the thickness of plate 32, the first of which is for the purpose of providing the surface for the attachment of the opposite plate 34 as by the conventional rivets; the other shoulder portion defining a longitudinal blade receiving slot between the plates 32 and 34.

Additionally, it will be noted that plate 32 has a pin 36 secured thereto and projecting at right angles through the aperture 37 in plate member 34, which pin serves to engage the blade 18 as

will be hereinafter set forth. Blade 18 is sharpened at both its top and bottom edges for convenience in two-directional cutting without turning the knife, and the opposite end thereof is split to define legs 38 and 39. It will thus be seen that we have provided for a rigid mounting of the blade 18 to reduce to a negligible minimum any tendency toward play during cutting operations to the end that the work may be neatly and accurately done.

In assembling the knife the carrier 14 is first inserted in recess 13, pin 16 of the carrier being centered in the helical spring 20 in recess 15. The carrier is manually held in this position and the legs 38 and 39 of blade 18 are inserted in the slot 35 in the carrier 14, straddling pin 36. Thumb screw 31 is then inserted through slot 30 in the handle 10 and screwed into plate 32 (see Figures 2, 4 and 6). As thumb screw 31 is tightened it causes plates 32 and 34 to be drawn together for the desired clamping of the legs 38 and 39 of the blade 18, thus preventing lateral or vertical play of the blade during normal use.

As will be noted from Figs. 1, 2 and 5, the deeper portion 11 of the handle 10 is tapered at its forward end into a lip 40 projecting under the bottom edge of the blade 18. The bottom edge of blade 18 is received by a slot 41 in the said lip 40 and the bottom of the recess 13. The purpose of this particular construction is to provide a thumb rest in close proximity to a cutting edge of blade 18 which is desirable in certain cutting operations. Accordingly, all danger of the pelts being caught between blade and handle are obviated. It will also be noted that the forward end of the top of the handle, between thumb piece 25 of latch 23 and the top cutting edge of blade 18, is streamlined as at 42, to prevent any catching of the furs in the cutting operation.

As heretofore explained, the furrier's knife forming the subject matter of this invention is provided with a pivotal retainer for a marking medium, such as chalk. The rear end of the handle 10 slotted as at 44 (see Figs. 5 and 6) to receive the retainer 45 pivotally attached therein as at 46, and having a marking medium, such as a chalk 47, clamped therein. The retainer 45 is provided with a projecting ear 48 which extends beyond the slot 44 as a convenient means of swinging the same out of the handle for use of the marking medium while in that position or for the replacement of the chalk.

The knife is also provided with means for marking by impression as will be noted from the

following: In cross-section (see Figs. 3 and 4) the handle member 10, at its deepest portion 11, is blade shaped, the bottom edge thereof coming to substantially a sharp edge 49. Under certain circumstances it is undesirable to make any mark of a permanent nature on the pelts and for this reason use of the edge 49 in marking by impression will be found highly desirable.

From the foregoing it is believed clear that we have provided a furrier's knife which is highly efficient for the purpose intended since it has all of the necessary attributes such as are required by one skilled in that particular art. While we have shown a preferred form of the invention, we wish it definitely understood that the principle of our invention may take many other forms and for that reason we desire protection according to the full scope of the appended claims.

The invention claimed is:

1. A furrier's knife comprising, a handle, a longitudinal recess therein extending rearwardly from the blade end, a blade carrier slidably received in said recess, a blade carried thereby, yieldable means normally urging the carrier out of the recess, a slot in the handle opening into said recess, a thumb-screw in said carrier projecting through said slot, a notch in the blade carrier, and a trigger having a toe normally and yieldably urged inwardly for engagement with the notch in said carrier.

2. A furrier's knife comprising, a handle, a longitudinal recess therein extending rearwardly from the blade end and terminating in a reduced bore at the opposite end, a blade carrier slidably received in said recess and having a pin received by said bore, a helical spring in the bore encircling said pin and normally urging said carrier out of the recess, a slot in the handle opening into said recess, a thumb piece threadably engaging said carrier and projecting through said slot, a notch in said carrier, and a trigger having a toe normally and yieldably urged inwardly for engagement with the notch in said carrier.

3. In a furrier's knife, a handle having a longitudinally extending recess therein, a blade carrier slidably received in said recess, a blade carried thereby, said blade carrier comprising a rigid piece having a shoulder at one end, a flexible piece attached to said shoulder and with said rigid piece defining a blade receiving slot, and means for drawing the flexible piece toward the rigid piece.
